UNITED STATES PATENT OFFICE

MINOT K. HOLMES, OF MUNCIE, INDIANA, ASSIGNOR TO HEMINGRAY GLASS COMPANY,
OF MUNCIE, INDIANA, A CORPORATION OF KENTUCKY

DESIGN FOR A BOTTLE

Application filed July 2, 1930. Serial No. 36,258. Term of patent 14 years.

To all whom it may concern:

Be it known that I, MINOT K. HOLMES, a citizen of the United States, residing at Muncie, in the county of Delaware and State of Indiana, have invented a certain new, original, and ornamental Design for a Bottle, of which the following is a specification, reference being had to the accompanying drawings, forming a part hereof.

As will be apparent from Figure 2, substantially identical designs are applied to both sides of the bottle.

I claim:

The ornamental design for a bottle, as shown and described.

In testimony whereof, I have hereunto subscribed my name this 30th day of June, 1930.

MINOT K. HOLMES.
